J. HARRIS

ELECTRICITY METER

Filed Dec. 27, 1926

Inventor:
Jesse Harris
By G. H. Grueg, Mfg.

UNITED STATES PATENT OFFICE.

JESSE HARRIS, OF LA FAYETTE, INDIANA, ASSIGNOR TO DUNCAN ELECTRIC MANUFACTURING COMPANY, OF LA FAYETTE, INDIANA, A CORPORATION OF ILLINOIS.

ELECTRICITY METER.

Application filed December 27, 1926. Serial No. 157,229.

My invention relates to electricity meters which are provided with covers held in place by rods carried by the meter bases, these rods projecting forwardly through the covers and having nuts threaded thereon which hold the covers in place. I provide an improved sealing means at the apertures in the covers through which said rods pass. In carrying out my invention I place a bushing around each rod and in the opening in the cover through which such rod passes, this bushing being laterally extended at its inner end to prevent the insertion of a tool that could stop the operation of the meter.

15 I will explain my invention more fully by reference to the accompanying drawing in which Fig. 1 is a sectional view of one form of meter with the cover thereon and Fig. 2 illustrates parts in separated relation.

20 The meter base in the meter shown is inclusive of a plate 1 formed with a forwardly projecting wall 2 to constitute a chamber. The motive element of the meter is suitably mounted upon the rear of a partition wall 3. The electro-magnets of the motive element of the meter, of which the current magnet 4 is shown, are upon the rear side of the wall 3, being surrounded by the wall 2 and enclosed within the chamber defined by 25 said wall. The upright meter spindle 5 is positioned by bearings which are carried by the wall 3 upon the front thereof, as is understood by those familiar with the art. The spindle carries a non-magnetic metallic armature disc 6 which extends into inductive relation with the magnets.

30 The cover 7, commonly of glass, is seated upon the front portion of the wall 2, a sealing gasket 8 being interposed between the cover and said wall. The cover is held in position by two rods 9 which are carried by the base and project forwardly therefrom through the cover. Two nuts 10 are threaded upon these rods and press upon the cover

to hold it upon its seat. The holes in the cover through which the rods pass are inwardly flared at their inner ends as indicated at 11. Bushings 12 are received in these holes and are furnished with flanges 13 at their outer ends against which the inner ends of the nuts are pressed. Washers 14, preferably of felt, surround said bushings and are interposed between the cover and said flanges. The inner ends of the bushings are flared or laterally extended, as indicated at 15, to fit the flaring inner ends of the holes in the cover through which the rods are passed. The rods and nuts may be sealed together as indicated at 16.

35 In prior devices, the bushings, covers and packing washers were separable and the bushings were so formed as to permit the insertion of wires into the interior of the meter casing to obstruct the operation of the meter. By flaring or laterally extending 40 the inner ends of the bushings, they, together with the packing washers, are permanently assembled with the cover and the flaring inner ends of the bushings prevent the insertion of tampering wires.

45 Having thus described my invention, I claim:

The combination with an electricity meter; of a supporting base therefor; a cover for the meter engaging said base; a rod projecting from the base and passing through an opening formed in the cover; a bushing in said opening and laterally extended upon its inner end, said rod passing through the bore of the bushing; a nut threaded upon 50 the outer end of the rod and pressing against the outer end of the bushing where the bushing is provided with a flange; and a washer surrounding the bushing and interposed between said flange and cover.

55 In witness whereof, I hereunto subscribe my name.

JESSE HARRIS.
